UNITED STATES PATENT OFFICE.

GEORGE S. GOSLEE, OF MASON CITY, IOWA.

CARBURETER.

SPECIFICATION forming part of Letters Patent No. 745,489, dated December 1, 1903.

Application filed September 20, 1902. Serial No. 124,211. (No model.)

To all whom it may concern:

Be it known that I, GEORGE S. GOSLEE, a citizen of the United States, residing at Mason City, in the county of Cerro Gordo and State 5 of Iowa, have invented certain new and useful Improvements in Carbureters, of which the following is a specification.

This invention relates to the production of gas for general consumption, and has for its 10 object to produce economically a good and uniform quality of illuminating-gas from any suitable liquid hydrocarbon—such, for example, as gasolene or naphtha.

The nature of the invention will clearly appear from the description and claims following, reference being had to the accompanying drawings, in which—

Figure 1 is a vertical section of apparatus embodying my invention, and Fig. 2 is a sectional view of the device for regulating the supply of gasolene to the tank which communicates directly with the generator.

Referring to the drawings by letter, A designates a cistern containing a sufficient supply of water to completely submerge the storage-tank B, supply-tank C, and generator D. The object of this is to maintain as nearly a uniform temperature as possible, and thus secure the greatest possible uniformity in the 25 quality of the gas produced. S is a drier through which the gas passes from the generator and is mounted above the floor F, which is some little distance above the top of the cistern.

The storage-tank is filled through a pipe G, the lower end of which is near the bottom of the tank, as shown. From this storage-tank the supply-tank C receives its contents through pipes H, H', and H² by the action of 35 a pump I. In the drawing the simplest type of a piston-pump is illustrated, though in practice a rotary pump of a common and well-known type may be used, driven by the same power that drives a blower for supplying air to the generator. As such pump, motor, and blower are of well-known construction and 40 form no essential part of this invention it has not been deemed necessary to illustrate them.

Another pipe J also communicates with the 45 pump and the storage and supply tanks and serves for the preliminary filling of the sup-

ply-tank and also for the emptying of the same whenever it may be necessary or for the drawing off of the heavier oil at the bottom of the supply-tank. This is done by closing the valves H³ and H⁴, opening the valve J' and the bib J², and operating the pump. The supply-tank communicates with the generator by a pipe K tapping the supply-tank near the surface of its supply of gasolene, and thus 55 carrying the light and volatile product into the generator. The bottom of the generator communicates with the lower part of the supply-tank, which is considerably lower than the bottom of the generator, by a pipe K'. This allows the heavier residuum from the generator to flow back into the supply-tank, whence it may be pumped out, as above described. The upper parts of the supply-tank and generator connect by a pipe K², the purpose of which is to equalize the pressure as 60 between the generator and supply-tanks.

In the supply-tank is mounted a float M, having a vertical stem M', terminating in a needle-point M². This needle-point fits a 75 small hole in the pipe-fitting H⁵, as shown in Fig. 2. While the apparatus is in operation, the pump causes a continuous flow of gasolene through the pipes H, H', and H². In case the supply in the supply-tank falls below a certain predetermined level the depression of the float opens the hole normally closed by the needle-point, and gasolene then flows down the pipe H² to supply the deficiency. 80 As soon as the liquid rises to the normal 85 level in the tank the needle-point closes the hole and the flow ceases. By this means a certain level of liquid is always maintained in both the supply-tank and the adjacent generator, and in the process of carburizing the 90 air has always to pass through the same depth of gasolene with corresponding uniformity in the result.

The carbureter or generator comprises a tank D, preferably cylindrical, a central air-pipe D', and a series of horizontal disks or diaphragms D² and D³. The former are provided with a central hole somewhat larger than the air-pipe, and the latter have a central hole fitting closely around the air-pipe, but 95 are of smaller diameter than the inside of the tank D, thus leaving a space between 100

their outer edges and the tank through which the air may pass. The air is thus forced in a circulatory zigzag course through the carbureter from bottom to top, whence it passes out through a pipe N, carburized by reason of its course between the plates in the carbureter.

5 In the pipe N is a trap N' for condensation from the ascending gas. A pipe O leads from the bottom of the trap back to the carbureter. This is provided with a check-valve O', which admits of the condensed moisture flowing back into the carbureter, but prevents the movement of gas in the opposite direction.

10 The upper parts of the supply-tank and carbureter are connected by a pipe P to equalize the pressure as between the tank and carbureter and prevent a partial vacuum in the former.

15 A pipe Q connects the pipe N above the trap with the storage-tank for a similar purpose. The vertical portion of this pipe P' permits the measurement of the gasolene in the storage, as by the insertion of a rod or the like.

20 Before reaching the gas-main R the gas passes through a drier S, fitted with a series of diaphragms S' and S'', similar to those in the carbureter, to give the gas a circular course. The spaces between the plates are 25 filled with some suitable absorbents—such as coke, for example.

The apparatus as thus constructed is adapted to the economical production of a gas of high illuminating power and very uniform 30 quality, characteristics which are of the utmost importance in the production of any gas and are especially difficult of realization in the management of gas from gasolene and like hydrocarbons.

35 Having thus described my invention, what I claim as new, and desire to secure by Letters Patent, is—

1. In a gas-machine, the combination of a storage-tank, a supply-tank at a lower level, 40 a pump adapted to draw liquid from the storage to the supply tank, a pipe communicating with said pump, with one terminal near the bottom and the other near the top of the storage-tank, a pipe leading from said storage-tank pipe to the supply-tank, and means 45 substantially as described for automatically

closing said supply-tank pipe, as the liquid in said tank reaches a certain level.

2. In a gas-machine, the combination of a storage-tank, a supply-tank, a pipe leading from near the bottom of the storage-tank to the pump and thence to the top of said tank, an intermediate pipe connecting the storage-tank pipe with the supply-tank, a float in said supply-tank, and a stem connecting with 55 said float, with a needle-point adapted to close said supply-tank pipe, whereby the supply-tank is fed by the overflow from the storage-tank pipe, and a uniform level of liquid is maintained therein.

3. In a gas-machine, the combination of a storage-tank, a supply-tank, a pump, a pipe communicating with said pump, with its suction end near the bottom of the storage-tank and its discharge end opening into the top 70 thereof, a branch therefrom leading downward to the supply-tank, a valve therein, a needle-point to close the same, with a stem extending to a float inside said supply-tank, a float, and another branch pipe opening into 75 the lower part of the supply-tank, a valve therefor, and valves for the storage-tank pipe, substantially as and for the purpose set forth.

4. In a gas-machine, the combination of a carbureter, a trapped gas-pipe leading from 80 the top thereof to the bottom of a drier, a drier substantially as described, and a drain-pipe leading from the bottom of the trap back into the carbureter, with a check-valve therein, substantially as and for the purpose set forth. 85

5. In a gas-machine, the combination of a storage-tank, a supply-tank, a carbureter, a drier and a trapped pipe connecting the carbureter and drier, supply-pipes leading from the storage to the supply and from the supply 90 to the carbureter, and pipes connecting the upper part of the supply-tank with the upper part of the carbureter, and the upper part of the storage with the trapped pipe, substantially as and for the purpose set forth. 95

In testimony whereof I affix my signature in presence of two witnesses.

GEORGE S. GOSLEE.
